(57) **CLAIM**

The ornamental design for a barcode printer, as shown and described.

DESCRIPTION

FIG. 1 is a front, top, left perspective view of a barcode printer showing my design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof;

FIG. 7 is a bottom plan view thereof;

FIG. 8 is a rear, top perspective view thereof; and,

FIG. 9 is a front, bottom perspective view thereof.

The broken lines depict portions of the barcode printer that form no part of the claimed design.
